(57) **CLAIM**

The ornamental design for a latch apparatus for retaining a flexible circuit cable within a receptacle mounted on a circuit board, as shown and described.

DESCRIPTION

FIG. 1 is a top perspective view of a latch apparatus for retaining a flexible circuit cable within a receptacle mounted on a circuit board showing our new design;

FIG. 2 is a front elevation view thereof;

FIG. 3 is a right elevation view thereof;

FIG. 4 is a rear elevation view thereof;

FIG. 5 is a left elevation view thereof;

FIG. 6 is a top plan view thereof; and,

FIG. 7 is a bottom plan view thereof.
